SWITCH MECHANISM

Hans Sengebush, Villa Park, Ill., assignor to
 Associated Electric Laboratories, Inc., Chicago,
 Ill., a corporation of Delaware

Application February 25, 1935, Serial No. 7,983

17 Claims. (Cl. 179—27.52)

The present invention relates in general to automatic switching apparatus, but is particularly concerned with the production of an improved switch of the flat type in which the wipers are moved in one plane in two directions at right angles to each other.

The main object of the present invention is to provide automatic switches of simple structure, which are rapid and accurate in operation and which take up only a small amount of mounting space as compared with the present day automatic equipment.

Another object of the invention is to provide improved switchbanks which are easily assembled, cheaper in construction, and reliable for use with switches of this type.

One of the features of the invention relates to a spring driven escapement mechanism controlled by a single spring and a single operating magnet for moving the wipers in both its selecting movements in the same plane.

Another feature relates to the changeover mechanism for changing the direction of travel of the wipers.

A further feature relates to the mechanism by means of which a single release magnet automatically restores the wipers back to their normal positions thereby tensioning the operating spring.

Other objects and features will be evident and a complete understanding of the construction and operation may be had from a perusal of the description in conjunction with the accompanying drawings, in which:

Fig. 1 is a perspective view showing the main part of the switch with certain details and spring assemblies omitted.

Fig. 2 shows two slightly different cross sections in part to more readily show the construction of the switch, the switchbanks and the mounting arrangement.

Fig. 3 shows a detail view of the spring assemblies operated by the changeover and release magnets.

Fig. 4 shows a detail view of the escapement controlling mechanism and the spring assembly operated by the operating magnet.

Fig. 5 shows a detail view of the wiper guard for preventing vibration of the wipers.

Fig. 6 shows a detail view of the changeover magnet and mechanism.

Fig. 7 shows the off normal spring assembly controlled by the escapement carriage.

Fig. 8 shows the cam spring assembly which

is operated by armature 93 when the wipers are operated to a point beyond the bank contacts.

Fig. 9 shows a cross section of one of the bank contact strips.

Fig. 10 shows a plan view of one of the bank strips.

Fig. 11 shows a front view of the mounting arrangement for mounting the bank strips shown in Figs. 9 and 10.

Fig. 12 shows a side view of the mounting arrangement.

Figs. 13 to 16, inclusive, show a modified bank structure.

Fig. 13 shows an end assembly view.

Fig. 14 shows a top view.

Fig. 15 shows a perspective of part of the bank assembly.

Fig. 16 shows in part a side view.

Referring now in detail to Figs. 1 and 2 the switch mechanism is supported on a flat base 20 plate 1 and two end brackets 2 and 3 which are rigidly secured to the base plate 1. Rods 4 and 5 extend between the two end brackets 2 and 3 and are rigidly secured thereto. Slidably mounted on the rods 4 and 5 are the main carriage 6 and the escapement carriage 7. Main carriage 6 comprises a metal plate provided with turned down edges, such as 40, having bushed holes therein through which the rod 4 extends. On the uppermost portion of the main carriage 6 is provided a turned up edge 42 and a flat portion upon which the guide plates 35 and 36 are mounted. The edge 42 and the assembled guide plates 35 and 36 act as guides for the wiper carriage 8 which is slidably mounted on carriage 6. The left-hand portion of carriage 6 is a recessed portion 43 in which a pinion 30 is rotatably mounted on shaft 31 secured to the carriage 6. The lower portion of carriage 6, or the left-hand portion as shown in the lower section of Fig. 2, is slightly bent so that it rests on top of the rod 5. A bracket 44 secured to the lower portion of carriage 6 is arranged to engage the rod 5 on the opposite side from the carriage 6 so as to form a guide to permit movement of the carriage 6 on rod 5 in a horizontal direction. The right-hand portion of carriage 6 is provided with turned down portions 41 and 40 in order to provide a mounting space for the changeover mechanism or locking dog 50 which is rotatably mounted on rod 51 which extends through the turned down portions 40 and 41. A leaf spring 90 secured to carriage 6 normally maintains the locking dog 50 in the position shown in Figs. 1 and 6.

15

35

40

45

50

55

The wiper carriage 8 is slidably mounted on main carriage 6 and has teeth on its left-hand edge which mesh with the pinion 30. A pin 29 mounted on the wiper carriage 8 rests against the top plate 32 and is provided to engage and operate armature 93 when the wipers are extended beyond the bank contacts. The top plate 32 is secured to the main carriage 6 in the manner shown in Fig. 1 and is provided with two pointers 33 and 34 which point to numerals on the bar 94 and escapement carriage 7 to indicate the position the wipers are operated to. The top plate 32 is also provided with a hole in which the rod 31 extends. As will be seen from the drawings plate 32, guide plates 35 and 36 and the upturned edge 42 guides the wiper carriage in its lateral, or forward, movement when the pinion 30 is rotated. The upper portion of wiper carriage 8 is secured to the bracket 83 which carries the wipers 76 to 81, inclusive.

The escapement carriage 7 is made of two pieces of sheet metal, the piece 9 being secured to the piece 7 in any suitable manner. The piece 9 has a hard rubber bushing at its left-hand end for operating the off-normal spring assembly 111 (Fig. 7) and is provided with teeth 38 on its lower edge which cooperate with the pawls 23, 29, and 68 in a manner to be described hereinafter. The left- and right-hand ends of the escapement carriage 7 have bent down portions 26 provided with bushed holes to permit carriage 7 to slide on rod 5. The left-hand end 26 of carriage 7 extends in a forward direction where a slotted or U-shaped portion extends over the rod 4 to act as a guide for the carriage. The front portion of carriage 7 is bent down in an L-shape as shown in Fig. 2 to form a rest for the toothed piece 9 which is riveted, or otherwise secured, to carriage 7. The bent down vertical portion has numbers thereon for indicating the lateral or forward movement of the wipers. The arm 94 likewise has numbers thereon for indicating the horizontal, or longitudinal, movement of the wipers. Both sets of numbers together with the pointers 33 and 34 indicate the set of bank contacts the wipers are resting on after the same have been moved. A hole 39 near the right-hand end of carriage 7 is provided to allow the catch 52 of the locking dog 50 to drop into and lock the main carriage 6 to the escapement carriage 7 so that the main carriage 6 will move horizontally with the escapement carriage 7. The left end piece 26 of the escapement carriage 7 also has a turned edge, shown more clearly in Fig. 2, to which the link 85 is pivotally connected. The link 85 is also pivotally connected to the spring actuated arm 86 which is pivoted at 88 to the base plate 1. The spring 89 at one end is fastened to arm 86 at 87, and at the other end is fastened to base plate 1. Spring 89 is normally tensioned to move the escapement carriage to the right as seen in Fig. 1. A spring and armature mounting plate 92 is secured to the end bracket 3 and is provided with turned edges to provide mounting space for armature 93 which is pivotally connected thereto. The off-normal spring assembly 111 (Fig. 7) is also mounted on this plate. The upper portion of end bracket 2 is turned to the left, as seen in Fig. 1, to form a mounting space for mounting the combed locking plate 45 and the back stop 46. The combed locking plate 45 has notches in its forward edge in which the upturned lug 53 of locking dog 50 may be positioned in order to lock the main carriage 6 to the switch frame when the locking dog 50 is operated from its normal

position. As long as the locking dog 50 is in its normal position the lug 53 passes underneath the combed locking plate 45 when the carriages 7 and 6 are moved to the right. When the armature 56 of the changeover magnet 57 is operated, the locking dog 50 is operated to disengage lug 52 from the hole 39 in carriage 7 thereby unlocking carriage 7 from carriage 6 and the lug 53 is projected into one of the notches in locking plate 45 dependent upon the initial movement of the carriages to the right. The lug 53 in engagement with one of the notches in the combed plate 45 locks carriage 6 to the switch frame to prevent further movement of carriage 6 when the escapement carriage is again moved. Lug 53 is maintained in its locking position after deenergization of the changeover magnet 57 by the lug 52 riding on top of carriage 7. Back stop 46 has a turned down end which engages and limits the back stop of the release magnet armature 66.

The iron core 11 of operating magnet 10 is secured to the base plate 1 by means of brass lug 98 and brass machine screws. A portion of the base plate 1 directly below the iron core 11 is cut out to reduce or prevent flow of magnetic flux 25 in the base plate 1.

Heel piece 12 of magnet 10 is formed of magnetic iron in the shape of a letter L and is fastened at its upper end to core 11 and near its lower end is fastened to the base plate 1 by means 30 of brass screws and a brass lug (not shown). Armature 13 is pivotally mounted to the base plate 1 in close proximity to the heel piece 12 so that the magnetic flux set up in the core 11 will extend from the core 11 through the heel piece 35 12 and armature 13 back to core 11. Armature 13 has two turned ears 14 through which the rod 15 extends for pivotally mounting armature 13 to base plate 1. Arm 18 on armature 13 extends at right angles from the main body of armature 13 and is provided with a hard rubber bushing for operating the spring assembly 110 whenever the armature is attracted by magnet 10. Lug 19 on armature 13 is also bent at right-angles to the main body of armature 13 and is provided to engage and operate the bent portion 21 of pawl 23 when the armature 13 is actuated. The end portion or detent 20 of armature 13 is bent in the manner shown to limit the movement of the escapement carriage 7 to one step when armature 13 and lug 19 has rotated the pawls 23 and 68 from engagement with the teeth 38 of escapement carriage 7. The pawl 23 is pivoted on rod 22 and is normally held in engagement with teeth 38 by spring 24 except when armature 13 is actuated. A lug 17 in base plate 1 acts as a back stop for armature 13 while spring 16 secured to armature 13 normally holds the armature against lug 17 except when magnet 10 is energized.

The U-shaped iron core 55 of changeover magnet 10 is secured to base plate 1 by means of brass screws and brass lugs 55' as shown in Fig. 6. Base plate 1 also has a cutout portion paralleling the iron core 55 to restrict or prevent the flow of magnet flux in base plate 1. Armature plate 56 65 is formed of a flat piece of magnetic iron and has two lugs on its lower edge which extend through holes in base plate 1. Two holes in these lugs are provided to allow the longitudinal portions of spring 56' together with the vertical 70 portion of spring 56' to hold the armature plate 56 in the position shown. The locking dog 50 has a curved portion 54 which by means of spring 90 normally holds armature 56 a short distance away from the core or pole piece 55. When the 75

changeover magnet 57 is energized armature 56 is attracted to pole piece 55 thereby rocking locking dog 50 on its pivot 51 against the tension of spring 90 to remove lug 52 from the hole 39 in carriage 7 and to project the lug 53 in one of the notches of combed plate 45 to lock carriage 6 to the switch frame. The operation of armature plate 56 also rotates the armature 58 on its pivot 59 secured to base plate 1. Armature 58 has a hard rubber bushing on its right-hand arm for operating spring assembly 109 whenever armature plate 56 is attracted. The middle spring of assembly 109 helps to retain armature plate 56 in its normal position. The spring assembly is mounted on base plate 1 in the manner shown in Fig. 3.

Heel-piece 62 of release magnet 61 is fastened to the left-hand pole piece and to the base plate 1 in a manner somewhat similar to that described for magnet 10. Armature mounting plate 64 is secured to heel piece 62 and is provided with bent ears to which armature 66 is rotatably fastened. A coil spring 65 is normally tensioned to maintain armature 66 against back stop 46. The lower portion of armature 66 is provided with a hard rubber bushing 67 for actuating spring assembly or interrupter spring 63 mounted on end bracket 2 whenever magnet 61 is energized to operate armature 66.

Release pawl 68 is provided with two turned ears 69 which are pivotally connected to armature 66 at 70. A spring 71 having one end fastened to armature 66 and the other end fastened to the turned up portion 72 of pawl 68 normally holds the bent left-hand portion 68' against teeth 38. Lug 73 in plate 1 is provided to limit the stroke of pawl 68 when magnet 61 is actuated. As previously stated whenever armature 13 or magnet 10 is attracted the lug 19 rotates the pawl 23 from engagement with teeth 38. This same rotation of pawl 23 also moves pawl 68' from engagement with teeth 38 to permit carriage 1 to move one step or until the detent 20 of armature 13 limits its further movement.

The fork shaped member 104 is secured to carriage 6 as shown in Fig. 5 and has arms 105, 106, and 107 on their upper ends to maintain the wipers separated and to prevent such wipers vibrating when the wipers are moved.

The female jack assembly 91 is mounted on base plate 1 near the rear of the switch as shown in Fig. 1. The male jack assembly 96 is mounted on the upright 95. The bank-contact assembly, such as shown in Figs. 13 to 16, inclusive, are shown in Fig. 2 in order to show the relative position of the switch wipers and the bank contacts, such bank contact strips being mounted on the uprights 95 in any suitable manner. In order to mount the switch the same is pushed in on two angle irons 99 on side uprights 97 until the jack assemblies mesh and until base plate 1 has been pushed to its proper position in which position said base plate is locked by a lug (not shown) on the angle irons 99.

A brief description of the switch operation will now be given. The switch as shown in Fig. 1 is in normal position with the operating spring 89 tensioned. When operating magnet 10 actuates its armature 13 to operate the escapement mechanism, pawl 23 and pawl 68' are disengaged from teeth 38. The escapement carriage 7 is then moved by spring 89 to the right one step until detent 20 of armature 13 engages one of the teeth 38. Since carriage 6 is locked to carriage 7 both carriages are therefore moved to the right

one step. The wiper carriage 8 is moved to the right with carriage 6. When armature 13 restores, spring 24 rotates the pawl 23 and spring 71 rotates the pawl 68' to engage teeth 38 of the escapement carriage. Subsequent operations of armature 13 move all the carriages to the right as just described to cause the wipers on the wiper carriage to be positioned opposite a desired set of bank contact strips. When the changeover magnet 57 is operated locking dog 50 at lug 52 unlocks carriage 6 from carriage 7 and at lug 53 locks carriage 6 to the switch frame to prevent further movement of carriage 6 to the right. Now when operating magnet 10 again operates the escapement mechanism, spring 89 again moves escapement carriage 7 to the right. Since the main carriage 6 is locked against movement, the teeth on the upper edge of escapement carriage 7 rotates pinion 30. The rotation of pinion 30 now moves the wiper carriage 8 in a forward or lateral movement to cause the wipers to successively engage the contacts of the selected bank strips and to stop on a certain set of contacts dependent upon the number of actuations of magnet 10. If for any reason the wipers are moved beyond the last contact set in their lateral movements, then pin 29 on carriage 8 strikes bar 93' of armature 93 to actuate said armature and spring assembly 112 which closes circuits (not shown) to restore the wipers to their normal position. In addition the first step of escapement carriage 7 to the right removes the rubber bushing on bar 9 of the escapement carriage from engagement with the off normal spring assembly 111 thereby causing the operations of such springs to their alternate positions. The operation of the magnet 10 also operates spring assembly 110 and the operation of changeover magnet also operates spring assembly 109.

In order to restore the switch wipers and carriages to normal release magnet 61 is intermittently operated to actuate armature 66. Each actuation of armature 66 operates pawl 68' to move the carriage 7 back one step to the left and also operates interrupter springs 63. Since carriage 6 is still locked to the switch frame, the movement of carriage 7 to the left rotates pinion 30 to cause the wiper carriage 8 to slide on carriage 6 until such time as pin 29 strikes plate 32. At this time lug 52, which has been riding on top of carriage 7, now drops into hole 39 in carriage 7 to cause lug 53 to unlock carriage 6 from the switch frame and to lock carriage 6 to the escapement carriage 7 so that all of the carriages are returned to the left in response to the continued operations of release magnet 61. When all of the carriages are restored to their normal positions the off-normal springs 111 are operated to prevent further actuations of release magnet 61. From the foregoing it will therefore be seen that the wipers of the switch are first moved step by step in a horizontal or longitudinal direction to select a set of bank contact strips, or a group of lines, and are thereafter moved step by step in a forward or lateral direction to select a set of contacts on the selected strips, or a line in the selected group.

Referring now to Figs. 9 and 10, beveled metal contact strips 121 are placed on both sides of sheets 120 of uncured bakelite in the proper locations in the form or mould and then subjected to the usual pressure and heat treatment to form the bank contact strips shown in Figs. 9 and 10. Figs. 11 and 12 show how these bank strips are mounted in the plates 123 which are provided

with notches 124 in which the bank strips are placed. The plates 123 are secured to channel irons 122 by means of machine screws as shown. The notches 124 facilitate the ease with which 5 the bank strips can be assembled and replaced. Such bank strips may be made of any reasonable length to provide the usual bank contacts for a plurality of switches. In bank strips of this type the usual multiple wiring between the bank contacts of adjacent switch banks such as is used 10 in the well known Strowger systems, is eliminated.

Figs. 13 to 16, inclusive, show a somewhat similar bank arrangement, the method of assembling 15 and the construction, however, being different. The bank strips for a plurality of switches are assembled in the following manner: The flat metal base plate 126 extends the width and length of the entire contact assembly. Base plate 20 126 is provided with holes through which the bolts, such as 127, extend to clamp the contact strips together. A row of separator insulators, such as 129, are next assembled on the bolts 127. Ten metal contact strips, such as 130, properly spaced, are now placed on the insulators 129. A 25 large insulating plate 131 somewhat similar in shape to base plate 126 but having cut-out portions, as shown in Fig. 15, for permitting longitudinal movement of the switch wipers, is next 30 assembled with the holes 128 guiding the plate 131 over the bolts 127 to the position shown in Fig. 15. Another set of contact strips 130 are then placed on this insulating plate 131 followed by a row of separator insulators 129 after which 35 another set of contact strips 130, another insulating plate 131, a further set of contact strips 130 and another row of separator insulators 129 are assembled in the order named. The entire bank assembly is built up in this manner until 40 the required number of bank contact strips are assembled. After the last row of separator insulators 129 are in place a metal plate 132 is placed on top of each insulator 129 and the bolts 127 are securely tightened. By referring to Fig. 16 45 it will be seen that the bank strips 130 are assembled on both sides of insulating plates 131 and that a space is left between adjacent sets of bank contact strips through which the wipers of the switch may be advanced in a lateral manner to 50 engage successive bank contact strips. Due to the base plate 126 and the different sections clamped by bolts 127, the entire bank assembly is rigid in construction and is easily mounted on uprights for cooperation with the wipers of a 55 number of switches as shown in Fig. 2.

Having described the invention, what is considered to be new and is desired to be protected by Letters Patent will be set forth in the following claims.

60. What is claimed is:

1. In an automatic switch, an escapement carriage, a single spring for supplying the motive power to move said escapement carriage, an escapement mechanism for controlling the operation of said escapement carriage, a magnet for operating said escapement mechanism to permit said spring to operate said escapement carriage, a wiper carriage moved in one direction in response to the first movements of said escapement carriage, and a pinion having teeth in mesh with teeth on said escapement carriage and with teeth on said wiper carriage for moving said wiper carriage in another direction in response to subsequent movements of said escapement carriage. 75

2. In an automatic switch, an escapement carriage, a single spring for supplying the motive power to move said escapement carriage, an escapement mechanism for controlling the operation of said escapement carriage, a magnet for operating said escapement mechanism to permit said spring to operate said escapement carriage, a wiper carriage moved in one direction in response to the first movements of said escapement carriage, a pinion having teeth in mesh with teeth on said escapement carriage and with teeth on said wiper carriage for moving said wiper carriage in another direction in response to subsequent movements of said escapement carriage, and means for rendering said pinion ineffective 15 to move said wiper carriage on the first movement of said escapement carriage and for rendering said pinion effective to move the wiper carriage only after the first movements of said escapement carriage. 20

3. In an automatic switch, an escapement carriage, a single spring for supplying the motive power to move said escapement carriage, an escapement mechanism for controlling the operation of said escapement carriage, a magnet for 25 operating said escapement mechanism to permit said spring to operate said escapement carriage, a wiper carriage moved in one direction in response to the first movements of said escapement carriage, a pinion having teeth in mesh with teeth on said escapement carriage and with teeth on said wiper carriage for moving said wiper carriage in another direction in response to subsequent movements of said escapement carriage, and indicating means for indicating both movements of said wiper carriage. 35

4. In an automatic switch, a switch frame, a main carriage slidable on said frame, a wiper carriage slidable on said main carriage, an escapement carriage slidable on said frame, a pinion rotatably mounted on said main carriage, teeth in said escapement carriage and in said wiper carriage in mesh with said pinion, locking means normally locking said main carriage to said escapement carriage, an operating spring normally tensioned to move said escapement carriage, escapement mechanism normally holding said escapement carriage from movement, a magnet for operating said escapement mechanism to first permit said spring to move all said carriages in 50 one direction, means for thereafter unlocking said main carriage from said escapement carriage and for locking said main carriage to said switch frame to prevent further movement thereof, said magnet thereafter operating said escapement mechanism to permit said spring to again move said escapement carriage in the same direction whereby the teeth on said escapement carriage rotate said pinion to move said wiper carriage in a different direction. 55

5. In an automatic switch, a switch frame, a main carriage, a wiper carriage, an escapement carriage, locking means normally locking said main carriage to said escapement carriage, an operating spring normally tensioned to move said escapement carriage, escapement mechanism normally holding said escapement carriage from movement, a magnet for operating said escapement mechanism to first permit said spring to move all said carriages in one direction, means for thereafter operating said locking means to unlock said main carriage from said escapement carriage and to lock said main carriage to said switch frame, said magnet thereafter operating 70 65 75 80 85 90 95 98 99 100 101 102 103 104 105 106 107 108 109 110 111 112 113 114 115 116 117 118 119 120 121 122 123 124 125 126 127 128 129 130 5 said escapement mechanism to permit said spring to again move said escapement carriage, means including a pinion rotated in response to the last movement of said escapement carriage for moving
 5 said wiper carriage in a different direction, means for restoring said escapement carriage to its normal position and for retensioning said spring, the first part of the restoration of said escapement carriage rotating said pinion to restore the wiper carriage from its last operated position, said locking means being returned to its normal position when the wiper carriage is restored to unlock the main carriage from the switch frame and to lock the main carriage to the escapement carriage,
 10 and the second part of the restoration of said escapement carriage thereafter causing all said carriages to be returned to their normal positions.

6. In an automatic switch, a switch frame, a main carriage slidably mounted on said switch frame, a wiper carriage slidably mounted on said main carriage, an escapement carriage slidably mounted on said switch frame, locking means normally locking said main carriage to said escapement carriage, means for operating said locking means to unlock said main carriage from said escapement carriage and for locking said main carriage to said switch frame, means including a magnet, an operating spring and an escapement mechanism for operating said escapement carriage, and means responsive to the operation of said escapement carriage for moving said wiper carriage and the main carriage in one direction in case said locking means is in normal position and for moving said wiper carriage in another direction in case said locking means is in its operated position.

7. In an automatic switch, a switch frame, a main carriage slidable on said frame, a wiper carriage slidable on said main carriage, an escapement carriage slidable on said frame, locking means normally locking said escapement carriage to said main carriage, means including a magnet, an operating spring and an escapement mechanism cooperating with said escapement carriage for moving said escapement carriage and said main carriage with its associated wiper carriage in response to the first operations of said magnet, a changeover magnet, means operated by said changeover magnet for operating said locking means to unlock said main carriage from said escapement carriage and to lock said main carriage to said frame, and means including said first magnet, said operating spring and said escapement mechanism for thereafter moving only said escapement carriage and said wiper carriage in response to the second operations of said first magnet.

8. In an automatic switch having a wiper carriage adapted to move in straight line motions in a plurality of directions in one plane to make a selection, a single escapement spring means for moving said carriage in both directions, a single operating magnet, means responsive to the first plurality of operations of said magnet for operating said escapement spring means to move said wiper carriage in one of its directions, and means responsive to a second plurality of operations of said magnet for operating said escapement spring means to move said wiper carriage in its other direction.

9. In a switch mechanism of the type wherein a carriage is first moved longitudinally and then laterally in the same plane to selectively position wipers carried by said carriage; the provision of a

single operating spring and a single step-by-step means for controlling the positioning of said wipers, and another single step-by-step means for restoring said wipers and retensioning said operating spring.

10. In a switch mechanism of the type wherein a carriage is first moved longitudinally and then laterally in the same plane to selectively position wipers carried by said carriage; the provision of a single operating spring and a single step-by-step means for controlling the positioning of said wipers, a changeover magnet for changing the direction of travel of said carriage and wipers, and another single step-by-step means for restoring said wipers and retensioning said operating spring.

11. In a selecting switch, fixed contacts, contacts movable for engagement with said fixed contacts, an element carrying said movable contacts mounted for movement in two different directions in the same plane, a spring for operating the movable contact carrying element in its two directions to make a selection of said fixed contacts, and an escapement magnet intermittently operated during both movements of said element to control said element in its two directions of travel.

12. In a selecting switch, fixed contacts, contacts movable for engagement with said fixed contacts, an element carrying said movable contacts mounted for movement in two different directions in the same plane, a spring for operating the movable contact carrying element in its two directions to make a selection of said fixed contacts, an escapement magnet intermittently operated during both movements of said element to cause said element to move step-by-step in its two directions of travel, and a changeover magnet for changing the direction of travel of said element.

13. In the bank contacts for a plurality of switches, a plurality of unit bank assemblies, each such unit comprising in combination a first series of parallel bank contact strips, a second series of parallel bank contact strips, and a single insulator extending parallel with said series of contact strips for separating said two series of strips, each series acting as bank contacts for a plurality of switches and as the multiple therebetween, rows of insulators separating each unit bank assembly from another and for enabling switch wipers to pass between such units, and means for rigidly holding said units and insulators together to form a series of bank contacts accessible to a plurality of switches.

14. In a telephone system, a plurality of switches, a single bank assembly for all said switches comprising a plurality of unit bank assemblies, each such unit comprising in combination a first series of parallel bank contact strips, a second series of parallel bank contact strips, and a single parallel insulator separating said two series of contact strips, each series of strips accessible to the wipers of a plurality of switches, and assembling means for separating each of said units to enable the switch wipers of all said switches to pass between adjacent units.

15. A bare wire bank multiple unit comprising a plurality of unit bank contact assemblies each unit bank contact assembly comprising a strip of insulating material having a series of parallel contact strips on either side thereof, and means for separately mounting each unit with sufficient space between adjacent units to permit the passage of switch wipers, said last means spacing off

sections of said contact strips as contact banks and covering sections thereof as multiple connections.

16. In combination in a bare wire bank multiple, a plurality of unit bank contact assemblies, each unit bank contact assembly comprising a unit strip of insulating material having a first series of parallel bank contact strips imbedded on one side of the unit strip and a second series 10 of parallel bank contact strips embedded in the other side of the unit strip, each contact strip having sections acting as contacts for a plurality of switches and other sections acting as a multiple between contacts, and supporting means having notches therein for holding and spacing said

unit strips with sufficient space between adjacent unit strips to permit passage of switch wipers.

17. A bare wire bank multiple for a plurality of switches, comprising a plurality of strips of insulating material each having a plurality of contact strips on each side thereof, said insulating strips mounted vertically in parallel relation with the contact strips running vertically on the strips of insulation, switches having wipers for contacting said contact strips in different horizontal planes, 10 and spacing elements holding said strips apart and providing open spaces between said strips where the wipers of each of a plurality of switches wipe over said contact strips.
